UNITED STATES PATENT OFFICE.

DAVID M. FULTON, OF BALTIMORE, MARYLAND, ASSIGNOR TO THE BALTIMORE COMMUTATOR COMPANY, OF BALTIMORE, MARYLAND, A CORPORATION OF MARYLAND.

COMMUTATOR.

Application filed April 7, 1919. Serial No. 287,976.

To all whom it may concern:

Be it known that I, DAVID M. FULTON, a citizen of the United States, residing at Baltimore city, in the State of Maryland, have invented certain new and useful Improvements in Commutators, of which the following is a specification.

This invention relates to an improved construction of commutator especially designed as a timer for internal combustion engines.

The invention is especially directed to improvements on the timer structure shown in U. S. Patent to Noah Number 1,175,901 granted March 14th, 1916.

One object of the present invention is to provide an improved construction of commutator having a hollow arm through which the wires may extend and be supported in a position to prevent them from becoming oil-soaked or wet, and to so construct the hollow arm as to permit access to the wires passing therethrough, throughout their entire length.

Another object of the invention is to provide an improved construction of commutator having a wire-supporting hollow-arm of such construction that the wires may be laid in place and connected to the several contact devices without the necessity of feeding the wires longitudinally through the hollow arm.

A further object is to provide an improved construction of commutator having a laterally-projecting wire supporting arm with cavities at one side thereof in which the wires may be laid, and to provide a detachable cover or plate that may be placed over said cavities and the wires therein after the wires have been connected to their respective contacts.

With these, and other objects in view, the invention is illustrated in the accompanying drawings, wherein,—

Fig. 1, shows an end elevation of a gear casing of an engine and a front elevation of a timer or commutator embodying my improvements and attached to said casing.

Fig. 2, illustrates the same in vertical longitudinal section,—the section being taken on the line 2—2 of Fig. 1.

Fig. 3, shows a cross-sectional detail

through the commutator as the same would appear if cut on the line 3—3 of Fig. 1.

Figs. 4, and 5, illustrate two views of the 55 detached commutator brush.

Fig. 6, shows a rear view of the detached commutator looking into the contact recess.

Fig. 7, illustrates a front view of the device with the cover and wires removed.

Fig. 8, shows an inner face view of the recessed side of the detached cover.

Fig. 9, illustrates a sectional detail through the cover as the same would appear if cut on the line 9—9 of Fig. 8 and

Fig. 10, shows a sectional detail through the commutator,—the section being taken on the line 10—10 of Fig. 7.

Referring to the drawing, the numeral 12, designates the front or end of a gear casing through which the end 13, of a gear shaft projects. The front side of this gear casing is shown as having an annular recess 15, around the projecting shaft-end, and my improved commutator or timer-device is designed to enclose the shaft-end and to seat in said annular recess.

An arm 16, is rigidly attached to the end of the shaft 13 and is swung through a circular path as the shaft revolves, and said arm is provided with a socket 17, at its outer end in which a contact brush 18, is yieldingly held: a spring 19, serving to press the brush outwardly.

During the travel of the arm with the shaft, the brush is caused to pass successively over several contact plates and to thereby produce sparks in the several cylinders of the engine to ignite the charges therein.

To effect this operation electrically it is 90 obvious that a system of wires or conductors must be connected with the contact plates, and it is the object of this invention to provide improved means for carrying the contact plates, protecting and caring 95 for these wires to avoid short circuits and misses in the firing operation, and at the same time permit ready access to the wires.

In carrying out the invention I provide a 100 commutator body 20, which I form of an insulating material and of a substance that will be proof against oils, greases and water.

This body 20, has an annular flange 21, which forms a wall about a circular cham-

ber 22, and in the present instance, a central recess 23, is provided in the body which communicates with, but is of a smaller diameter than, the circular chamber, whereby 5 a flat annular face 24, is produced between the flange 21, and the recess 23.

I may, and preferably do provide the inner side of the flange wall 21, with an annular groove 25, whereby to facilitate the 10 escape of oils that might work into the chamber 22, and to aid in this, I also taper the inner surface of the flange wall so that drainage may be more completely effected by draining the oil to the bottom and allowing the same to run out through a port 15 14, which I provide in the lower side of the flange 21.

The commutator body 20 on its exterior is somewhat tapered from its inner toward its 20 outer side, and at the reduced outer side is provided with an arm 26, which projects laterally therefrom.

The outer side 27, of the body is straight and flat in a direction at right angles to the 25 axis of the chamber 22 and recess 23, and the arm 26, extends laterally from or is a continuation of said straight flat side. A rib 28, extends from the side of the body along the under or inner side of the arm 26, and serves 30 as a brace or bracket therefor.

The outer sides of both the body and the arms are provided with a recess 29, which extends from the body-part and longitudinally through the arm. Near the outer end 35 of the arm the recess has a concave enlargement 30, and from said enlargement to the free end, said arm is provided with a concave passage 31, for a purpose that will presently be explained.

40 By reference to Figs. 7 and 10, of the drawing it will be noted that the body and arm have a projecting bead or flange 32, around and along their marginal edges and that a lateral passage or groove 33, extends 45 from the recess 29 through the bead or flange 32, at one side of the arm. The purpose of this groove or passage will also presently be explained.

By reference to Figs. 3 and 6 of the drawings 50 it will be noted that the annular face 24, in the circular chamber 22 of the body is provided with a plurality of contact plates 34, which are uniformly spaced around the central recess 23. Each of these 55 plates is embedded in the insulating material of the body so that its flat face that is exposed in the chamber 22, will be flush with the annular face 24, in order that the contact brush 18, when making its circular 60 sweep around the face 24, may pass over the contact plates successively and without meeting any obstruction when passing on to or from the plates.

The material of which the body 20, is 65 formed is a composition and has a density or

hardness equal to the metal of which the contact plates 34, are formed, and the result is, that after long periods of use it has been found that the brush 18, does not cause a greater wear on the face 24 than on the 70 contact plates, or vice versa.

Each contact plate has a metallic stem 35, extending outwardly through the body from its embedded side, as best seen in Fig. 3, of the drawing, and the outer ends of these stems project from the body and are exposed in the recess 29. These exposed stem-ends are screw-threaded because they are to serve as binding posts for the attachment of conductor wires. 80

One or more of the threaded stems 35, may project sufficiently from the recessed side 29, of the body to also serve as securing bolts for a cover, which latter will presently be described. 85

Suitable bolt holes 36, are provided in the arm 26 and inside of the bead or flange 32, also for the passage of suitable fastenings to hold the cover in place.

A cover 37, shown in detail in Figs. 8 and 9 of the drawing has a circular enlarged end 38, and a lateral extension 39 projecting from one side thereof. Both the circular enlargement and the lateral extension have depending bottom flanges 40 and 41, which are spaced with respect to each other in order to provide a bottom channel or groove 42. 90

The under side of the cover is provided with a recess 43, which extends laterally at the under side of the extension 39 and is 100 deeper and of a semi-circular form at 44, near the outer end of the extension.

A semi-circular groove 45, is also provided at the bottom or inner side of the cover near the outer end of the extension 39, 105 and this groove 45, registers with the groove 30, in the arm 26, when the cover is in place, whereby to provide an annular packing channel as and for a purpose also presently to be explained. 110

At the extreme end of the lateral extension 39, I provide a semi-circular end-recess 46, which registers with the concave passage 31 in the end of arm 26, and with the latter forms a circular opening for the passage of a cable 47, containing the conductor wires. 115

One or more perforations 48, is or are provided in the circular enlarged end 38, of the cover for the passage therethrough of the stem or stems 35, by which the cover is to be secured in place at that end, and at or near the end of the extension 39 I provide the latter with a plurality of perforations 49, which register with the perforations 36, in the arm so that bolts or equivalent fastening devices 50, may be passed therethrough to secure the cover at that end. 120

I further provide the under side of the cover with a lateral passage 51, which passes 125

through the flanges 41 and 42 and opens at the outer side of the cover.

On the outer side of the enlarged end of the cover I provide a circular recess 52,

5 which receives a projection on the end of a spring arm 53, that presses the cover and body toward the gear case of the engine and seats the flange 21, of the body in the recess 15, of the case so it may be oscillated.

10 An eye 54, projects from one side of the commutator body 20, at the rear of the arm 26, so that an operating lever 55, may be engaged with said eye to oscillate the body to shift the latter and the contact plates 34, 15 therein with respect to the shaft 13, and thereby advance or retard the spark in the cylinder.

The commutator is especially designed to permit complete access to all the wires 20 throughout their length during attachment or detachment of the wires with or from the stems or binding posts 35.

These wires in the form of a cable 47, are led to the end passage 31, of the arm 25 26.—a packing 56, being placed in the groove 30, to partly encircle the cable. Beyond the packing the several wires in the cable are separated and led to and secured 30 on the stems 35, while an additional wire 57, which is used in the lighting system is extended from the cable laterally through the passage 33, at the side of the arm.

After the wires have been connected, the 35 cover 37, is then fitted onto the body and arm,—the flanges 40, 41, straddling the bead 32, on the body and the bead therefore fitting into the channel 42, so that a tight 40 joint is made between the body and the cover. Packing material is also placed in the groove 45, of the cover so that a complete 45 tight joint will be made all the way around the cable so as to exclude grease, oils, or water. Fastening devices are then passed through the perforations 36 and 49, and nuts are screwed onto the threaded ends 45 of the stems 35 so that the cover is rigidly secured in place.

The commutator is then placed in position 50 on the gear case with the lateral arm 26, projecting upwardly and the wires will all be supported in an elevated position, the arm directing the same to the top of the engine and at the same time confines the wires so they will not interfere with a person working about the engine.

Any oil or grease that might find its way 55 into the chamber 22, of the commutator from the shaft 13, will drain off through the grooves 25 and port 14 from a point well below the cable.

It is to be particularly noted that wires 60 may be connected to the respective binding posts while the cover is entirely removed and the posts are fully exposed and after 65 the connections are made the cover may be

attached. This construction very materially simplifies the wiring operation and permits ready access to the wires throughout their length.

By providing the channel 25, and escape 70 port 14, any particles that might be formed by wear on the brush or contacts may work down into chamber 22 and escape through the port.

Having described my invention what I 75 claim is,—

1. A timer device for the ignition system of an internal combustion engine, having in combination a body and a cover therefor,—the body having a circular enlargement at 80 one end with a circular cavity formed in its inner face, and at the opposite or outer face said body having a marginal flange which forms a recess which is circular at one end and elongated in a direction laterally from 85 said circular end, contact devices in the circular cavity in the inner face of the body and having binding posts which extend through the body and terminate in the recess at the outer face of the body, wires 90 attached to the binding posts and laid along the recess at the outer side of the body and a cover having marginal flange means around its inner face to lap the marginal flange on the outer face of the body and 95 seal the wires and contact devices in the outer body-recess.

2. A timer device for the ignition system of an internal combustion engine having in combination a body-part having a circular portion and an integral laterally-projecting arm portion said body-part being provided with a cavity at its inner side and having a recess at its opposite or outer side which latter recess extends laterally along the outer 100 face of said lateral arm; contact devices exposed in the said body-cavity at the inner side and having binding posts that project through the body and terminate in the said recess at the outer side; wires laid loosely in said outer recess of the said body and arm and attached to the ends of the binding posts therein, and a cover over said body recess and having a semi-circular passage through which the wires may pass to 110 the outer side of the body.

3. A timer casing comprising a moulded body-part having a deep recess formed in its inner side to receive the rotating brush on the end of a shaft and said body part being provided with a laterally projecting integral arm and the inner face of said arm having a shallow recess formed therein which recess is bound by marginal walls 120 with a concave packing notch near the end thereof, contact devices exposed in the deep recess at the inner side of the body and extending through the body to the shallow recess at the outer side of said body, a detachable cover plate having a flat circular 125 130

portion at one end and a lateral arm-portion extending therefrom said cover plate having a marginal edge at its inner face that laps the marginal walls on the outer side of the body-part and said arm portion of the cover plate having a concave packing notch to register with the packing notch in the arm portion of the body, whereby igni-

tion wires may be laid in the recess at the outer side of the body and connected to the contact devices therein and the cover afterward secured thereover, and the concave notches packed to prevent entrance of oil.

In testimony whereof I affix my signature.

DAVID M. FULTON.
